UNITED STATES PATENT OFFICE.

JOHN C. A. ANDERSON, OF WILMETTE, ILLINOIS, ASSIGNOR TO RELIANCE ELEVATOR CO., OF CHICAGO, ILLINOIS, A CORPORATION OF ILLINOIS.

ELEVATOR-CONTROL SYSTEM.

Application filed March 19, 1925. Serial No. 16,709.

My invention relates to elevators and more particularly to a system for controlling the operation of elevators.

It is a purpose of my invention to provide means for controlling the operation of elevators comprising push button controlling devices and means associated with said devices to indicate the position of the elevator car to the operator of the push button switch device. The push button switch devices preferably comprise a pair of push buttons, one of which, while depressed, closes a circuit whereby the elevator car is caused to move upwardly and the other of which when depressed closes the circuit which causes the elevator car to move downwardly. The controlling device preferably comprises a pair of said push buttons at each floor level or landing and an indicator operated by the movement of the car associated therewith to indicate the exact position of the car relative to the various floor levels or landings provided within the range of movement of the elevator. Said indicating means preferably comprises a pointer that moves along a dial to indicate the landings along the travel of the elevator car.

In push button controlled elevators of the type referred to above, in order to provide safety of operation of the elevator, the doors and the controlling devices are so interlocked that any door can only be opened when the car is at the floor level or landing at which the door is located and so that the elevator car cannot be operated unless all the doors at all the landings or floor levels are closed. As the indicating device is intended to make it possible to operate the elevator so as to move the same to a floor level different from that at which the operator of the push button device is located, or to move the same from a floor level different from that at which the operator of the push button device is located, it would obviously be impossible to move the car if someone had previously moved the same to a floor level, opened the door at said floor level and left the car with the door open. This would cause the circuits to remain open controlling the operation of the car both in an upward and a downward direction and would make it impossible to move the car by depressing the button at a remote floor level while the door remains open.

It is accordingly, a purpose of the invention to provide signal means to draw the attention of the person at the floor level at which the car is located and at which the door has been left open to the fact that someone at another floor level desires to move the car and cannot move the same because the door is open. Said signal means preferably comprises a bell or other audible signal carried by the elevator car which is actuated upon depressing either of the two push buttons forming a part of any one of the push button devices. Said push buttons are preferably provided with an auxiliary contact for completing the signal circuit when the operating circuit is open, said circuit being completed by means of a relay when said push button is depressed and the controlling circuit is open.

It is another purpose of the invention to provide means for adjusting the floor indicating means or other landing indicating means on a dial so that the indicator pointer member will correctly indicate the floor levels or landings at which the car is located to thus make it possible to exactly locate the car at a desired level or landing by the push button devices referred to. The indicator is operated by the movement of the car and means is provided whereby the movement of the indicator or pointer is directly proportional to the movement of the car at all times.

Other objects and advantages of the invention will appear as the description of the accompanying drawings proceeds. However, I desire to have it distinctly understood that I do not intend to limit myself to the exact details shown or described, but that I intend to include as part of my invention all such obvious changes and modifications of parts as would occur to a person skilled in this art and as would fall within the scope of the claims.

In the drawings:

Fig. 1 is a view in vertical section of a portion of a building showing an elevator shaft with the elevator and the controlling means therefor;

Fig. 2 is a view in elevation of the indicator operating means employed in connection with my improved control device;

Fig. 3 is a fragmentary elevational view of a portion of the elevator shaft or hatch-

way showing my improved push button control device in position adjacent the hatchway at a landing or floor level;

Fig. 4 is an enlarged elevational view 5 of one of the push button control devices;

Fig. 5 is a diagrammatic view showing the circuit connections employed in connection with my improved control system; and

Fig. 6 is a fragmentary section taken on 10 line 6—6 of Fig. 4.

Referring in detail to the drawings, in Fig. 1 is shown an elevator car 10 that operates in the shaft or hatchway 11 and which is raised and lowered by means of the hoisting mechanism 12 having the brake 13 and the motor 14 associated therewith, the usual counterweight 15 being provided in conjunction with the car 10. Secured to the elevator car 10 at 16 is a cable 17 that is 20 wound a plurality of times around a drum 18 and then passes downwardly so as to hang in a loop in the hatchway, the opposite end thereof being also secured to the elevator car at 19. A pulley 20 is free to roll 25 on the cable 17 and is provided with a weight 21 secured thereto so that the cable will ordinarily take a position similar to that shown in Fig. 1 with the pulley 20 at the lowermost point thereof due to the provision of the weight 21. Thus, the cable 17 will always be held under tension by means of the weight 21, the tension therein being due to the weight 21 rather than due to any movement of the elevator car 10, the movement 30 of the car merely causing a change in position of the weight 21 relative to the car without changing the position of the weight 21 relative to the drum 18. Thus, the change of position of the car 10 will have 35 no effect on the length of the cable. As the distance between the drum 18 and the pulley 20 will always be the same, the amount of rotation of the pulley 18 will be directly proportional to the movement of the car 10.

45 The drum 18 is connected through the reduction gear 22 with a shaft 23 carrying the pulley 24 to which one end of the flexible metallic band 25 is secured. Said band 25 is suspended within the hatchway and is 50 provided with a weight 26 to hold the same taut at all times. A plurality of similar metallic band members 27 are secured to the member 25 at fixed points by means of the securing members 28 which may be in 55 the form of clamps or any other desired securing means. The flexible band members 27 run over pulleys 29 making preferably a complete turn therearound as indicated at 30.

60 The pulleys 29 are mounted on shafts 31 so as to rotate therewith and said shafts 31 have the indicator members or pointers 32 mounted thereon so as to rotate therewith. The pointers or indicator members 32 are 65 each associated with a push button control

device 33, each of which is provided with a push button 34 controlling the upward movement of the car and a push button 35 controlling the downward movement thereof. The pointer 32 cooperates with a dial 70 provided with the indicator members 36 which indicate the floor levels or landings at which the car is adapted to stop. Preferably, the indicator members 36 are adjustably mounted on the dial, a slot 37 being 75 provided for sliding the same along to the proper position for the same, suitable clamping means 38 being provided for holding the indicator members 36 in adjusted position. Said indicator members are preferably 80 provided with tapered projections 39 adjacent the path of the tapered ends of the pointer 32 so as to aid in aligning the pointer 32 exactly with the tapered end of the projection 39 of an indicating member 85 36 to align the elevator car properly with the floor level or landing at which it is desired to stop the same. The members 36 are, of course, adjustable so that when the pointed end of the pointer is in exact alignment with the pointed end of the projection 39 on a given member 36, the car will be substantially level with the floor that the member 36 indicates.

It will accordingly be seen that the elevator car can be moved from any desired floor to any desired floor by means of any one of the push button control devices whether located at either of the floor levels referred to above or not, as the operator can 100 determine the exact position of the car while controlling the operation of the same by means of the push buttons. The push button control devices are of the well known type wherein the button must be continuously depressed to cause the car to move in a desired direction. Thus, if the "up" button is depressed, the car will move upwardly as long as the depression of the button continues. However, as soon as the button is 110 released, the circuit is broken and the car stops. The same thing applies in connection with the "down" button.

The control means for the elevator car is ordinarily interlocked with the doors at the 115 various floor levels or landings by means of which the hatchway can be entered so that the elevator car will not operate when any one of the doors is left open and so that the doors cannot be opened except when the 120 car is at the floor level of the door that is desired to be opened, this being a customary arrangement in order to prevent accidents by moving a car from a floor level while the same is in use or while the same is being 125 loaded or unloaded and also to prevent any one from walking into the hatchway when the car is not at the floor level at which the person attempting to enter the hatchway is 130 located. Due to the provision of the means

preventing operation of the car when the door is open, it would be obviously impossible to move the car from a floor level at which the car is stationed if the door at said floor level is open. This acts as a safety device when the car is actually being used at the floor level and is being loaded or unloaded at said floor level.

However, frequently doors are either 10 completely closed or not closed at all, due to carelessness of persons operating the car after said persons have finished using the same. In order to call the attention of some one near the car to the fact that such a condition exists, signal means is provided which 15 operate when a push button is operated for the purpose of moving the car and the door is in open position, said signal means being located on the car and being preferably a 20 bell or other audible signal.

The operation of the signal means will be more clearly understood by reference to Fig. 5 in which the circuit connections necessary for the operation of the signal are shown. 25 In said figure the switch board 40 is shown as being provided with a positive terminal 41 and a negative terminal 42, the positive terminal 41 being connected by means of the conductor 43 with the conductors 44 and 30 45 at each of the landings or floor levels which leads to the contacts 46 and 47 associated respectively with the push buttons 34 and 35. Said push buttons are provided respectively with the bridging members or 35 movable contact members 48 and 49 which are adapted to bridge respectively the contacts 50, 51, and 46, and the contacts 52, 53, and 47. The contacts 50 are all connected by means of the conductor 54 and the contacts 52 are all connected with the conductor 55, while the central contacts 51 and 53 are all connected with a common conductor 56. Thus it will be seen that every time a button 34 or 35 is depressed, the movable contact member associated with said button will 40 make three contacts, the purpose of which will be explained below.

Leading from the negative terminal 42 is a conductor 57 which has the door operated switching members 58 interposed therein, said conductor 57 leading to the emergency switch 59 provided on the car 10, from which the conductor 60 leads to a terminal 61 provided on the switchboard 40. From said terminal 61 a conductor 62 leads to the stationary contact 63 of a relay 64 having the movable contact 65 with which the conductor 66 is connected which is connected with both the conductors 54 and 55 through the controller coils 67 and 68 respectively, said controller coils being respectively coils controlling up and down movement of the elevator car 10. The elevator car is further provided with a push button switching device 65 similar to those located at the various floor

levels or landings but having each only two contacts cooperating with the movable contact members. The push button controlling upward movement is designated by the numeral 34' and the push button controlling downward movement by the push button 35'. The push button 34' is provided with the contacts 50' and 46' while the push button 35' is provided with the contacts 52' and 47'. The conductor 54 is connected with the contact 50', the conductor 55 is connected with the contact 52' by means of the conductor 55' and the conductor 43 is connected with the contacts 46' and 47' by means of the conductor 43'.

It will be evident that if a button 34 is depressed or the button 34' is depressed, the current will flow from the terminal 41 through the conductor 43 and through the movable contact of the push button member 34 or 34' to the conductor 54 through the coil 67 and to the terminal 61 from said terminal 61 through the conductor 60 to the emergency switch 59, then through the conductor 57 and through all the door switches 58 to the negative terminal 42, thus energizing the coil 67 to cause the controller mechanism to move the car in an upward direction.

In a similar manner, if a button 35 or 35' is depressed, the positive terminal 41 will be connected with the negative terminal 42 through the conductors 43, the push buttons 35 and 35', the conductor 55, the coil 68, the conductor 60, the emergency switch 59, the conductor 57 and the door switches 58 to the negative terminal 42, thus energizing the coil 68 on the controlling device causing said controlling device to move the car in a downward direction.

The signal means for calling the attention of persons adjacent the car 10 to the fact that one of the switches 58 is open due to the door being open at the level at which the car is located comprises the electric bell or other audible signal means 69. The conductors 70 and 71 lead from said signal means 69 to the contacts 72 and 73. The contact 72 is stationary and the contact 73 is movably mounted forming part of the movable means of the relay 64. The relay 64 is provided with a winding 74 which is connected between the negative terminal 42 and the terminal 61 on the switchboard 40. Any suitable means for supplying current to the signal devices 69 may be interposed in one of the conductors 70 or 71, a battery 75 being shown in Fig. 5 although it is evident that a door bell transformer or similar device may be substituted for the battery. The conductor 56 is also connected with a terminal 61 through the resistance 76, as will be evident from Fig. 5.

The resistance of the winding 74 is such that when the circuit through the door oper-

ated contact or switching members 58 is closed by depression of any one of the buttons 34, 34', 35, or 35', the winding 74 will be short circuited, the current passing through the coil 67 or 68, as the case may be, which is of relatively low resistance. At the same time that either a button 34 or 35 is depressed, a connection is made between the conductor 56 and the conductor 43, thus connecting the terminal 61 with the positive terminal 41 through the conductor 56 and the resistance 76. If the circuit in which either the coil 67 or 68 is located is open due to the fact that any one of the door operated switches 58 or the energizing switch 59 is left open, the current from the positive terminal 41 will flow through the conductor 43 through the push button contacts and through the conductor 56 to the terminal 61 and then through the winding 74 of the relay 64 causing the movable contact member of the relay to move upwardly.

It will be evident that at this time, the winding 74 is not short circuited because the circuit in which either the coil 67 or 68 is located is open. The movement of the movable contact member of the relay 64 will cause the contact 73 to engage the contact 72 and simultaneously cause the contact 65 to leave the contact 63, thus preventing the energizing of the coils 67 and 68 by a flow of current through the same without passing through the conductors 57 and 60 in which the safety switching devices are located. When the contacts 72 and 73 are in engagement, the circuit of the signal 69 is closed causing the same to be actuated and calling attention to the fact that one of the doors controlling the switches 58 or emergency switch 59 has been left open. Upon closure of the door, the signal will cease to operate due to the short circuiting of the winding 74 of the relay and the car will begin its movement due to energization of the proper coil 67 or 68, as the case may be.

Having thus described my invention what I desire to claim and secure by United States Letters Patent is:

1. In a device of the character described an elevator car, and means for controlling the operation of said car comprising a manually movable device which when in one posi-

tion causes said car to move and in another position causes it to stop and means indicating the position of said car at all times relative to said device mounted adjacent said device in view of the operator thereof.

2. In a device of the character described an elevator car, and means for controlling the operation of said car comprising a manually movable device which when in one position causes said car to move and in another position causes it to stop, comprising switching means controlling the upward movement of said car, and switching means controlling the downward movement of said car, and means indicating the position of said car at all times relative to said device mounted adjacent said device in view of the operator thereof.

3. In a device of the character described an elevator car, and means for controlling the operation of said car comprising a manually movable device which when in one position causes said car to move and in another position causes it to stop and means operated by the movement of said car to indicate the position of said car at all times relative to said device mounted adjacent said device in view of the operator thereof.

4. In a device of the character described, an elevator car, and means for controlling the operation of said car comprising a manually movable device which when in one position causes said car to move and in another position causes it to stop at each floor level, and means at each floor level indicating the position of said car, mounted adjacent each of said manually movable devices.

5. In a device of the character described an elevator car, and means for controlling the operation of said car comprising a manually movable device which when in one position causes said car to move and in another position causes it to stop and means mechanically connected with said car for indicating the position of said car mounted adjacent said device, said indicating means comprising a movable pointer and a dial having adjustable floor level indicating means thereon.

In witness whereof, I hereunto subscribe my name this 16th day of February, A. D. 1925.

JOHN C. A. ANDERSON.
